UNITED STATES PATENT OFFICE.

MORRIS SHEINMAN, OF NEW YORK, N. Y.

LOCK.

Application filed April 10, 1923. Serial No. 631,127.

This invention relates to improvements in locks and more particularly to door locks, one of the objects of my invention being to provide a jimmy-proof lock in which a ⁵ half turn of the bolt will effectively prevent separation of the lock and keeper whereby the door can be opened.

A further object is to provide a lock which can be used as a latch and which can ¹⁰ be turned to a jimmy-proof position at the will of the operator. The lock can be operated from within the house by a knob and from the exterior by the person only ¹⁵ who has the proper key.

¹⁵ A further object is to provide a lock, the bolt of which, when in latching position, is free to move into the lock casing against the action of a spring, but which when in jimmy-proof position is also locked against ²⁰ longitudinal movement and cannot be forced into the lock casing.

Other objects and advantages of my improved construction will appear as the specification progresses.

²⁵ In the accompanying drawings, which illustrate an embodiment of my invention; Fig. 1 is a face view of the lock, the cover plate being removed to show the parts, and the bolt being shown in ordinary engagement with the keeper;

Fig. 2 is a view of the underside of the cover plate;

Fig. 3 is a sectional elevation of the lock and its connection to the door, the section being taken on the line 3—3 of Fig. 1;

Fig. 4 is a section taken on the line 4—4 of Fig. 1;

Fig. 5 is a section taken on the line 5—5 of Fig. 1;

Fig. 6 is a section taken on the line 6—6 of Fig. 2;

Fig. 7 is a face view of the keeper plate with the bolt turned to jimmy-proof position;

⁴⁵ Fig. 8 is a view similar to Fig. 1 and shows the lock parts as they appear when the bolt is drawn back to unlatched position; and

Fig. 9 is a view similar to Fig. 1 showing the parts as they appear when the bolt is revolved to jimmy-proof position.

Referring to the drawings in detail, 10 denotes the lock casing in which is slidably mounted a bolt 11 which projects through the side wall 12 of the casing to normally engage a keeper 13. The inner

end of the bolt is flanged to limit its outward movement against the action of a spring 14 which is wound around the square shank 15 which is formed on the bolt and ⁶⁰ which slides across an upstanding wall 16 of a cam slide 17, to be later referred to in detail. The inner end of the spring 14 abuts against a collar 18 which is provided with a square bore through which the shank 15 can slide. The shank 15 passes between two posts 19 which keep the bolt in alignment and which are preferably cast integral with the casing 10. The shank in that portion which lies between ⁷⁰ the posts is rounded on its diagonally opposite edges as at 20 so that the bolt 11 can be revolved a half turn. Beyond the posts, the shank is reduced to receive loosely an arm 21 whose outer end 22 is widened to ⁷⁵ provide a support 23 which slides on the bottom of the casing, the upper end of the support being adjacent the under surface of the cover plate 24 so that any tendency of the arm 21 to swing upwardly is prevented. ⁸⁰ The arm is retained on the end of the shank 15 by a washer 24' and screw 25. It is thus seen that the bolt can be freely moved to the limit of its inward travel against the spring 14 when in the position shown in Fig. 1 and shown as moved in Fig. 8. This provides the latching feature when the door is swung closed.

The casing 10 will, of course, be mounted on the inside face of a door, a portion of ⁹⁰ which is indicated as at 25' (see Fig. 3) and the keeper 13 fixed on the face of the door frame 26 so that a portion thereof lies adjacent the end of the casing 10. The lock for operating the bolt may be of any well known type, preferably of the pin cylinder type, operated with a paracentric key, and will be mounted within the door as shown in Fig. 3. The pin cylinder 27 will revolve a hollow cylinder 28 carried by the casing cover through the medium of a spindle 29 which projects into the cylinder 28 through a suitable slot 30 in the latter. The cylinder is flanged at its inner edge as at 31 to overlie two washers, the lower of which 32, carries a cam operating arm 34 and is cut out on its periphery as at 35 to allow a relative movement between washer 32 and upper washer 36, which is provided on its periphery with a downwardly and outwardly extending projection 37 which lies within the cut out portion of washer 32. ¹⁰⁰ ¹¹⁰

The bottom or knob side of the casing 10 is provided with a like cylinder 38, the outer end of which is shaped to provide a knob 39, the lower washer 40 in this instance also being provided with a cam operating arm 41 and a peripheral cut out portion 42, while the upper washer 43 is provided with a bolt operating finger 44 and a dowel 45 which extends downwardly 10 into the cut out portion 42. The cam arm 41 is provided with an upstanding pin 46 which engages in a suitable socket in the end of cam arm 34 above referred to, so that either a key or the knob will operate 15 the lock in the same manner.

The cam slide 17 is shaped to provide a cut out 47 through which the cam arm 41 may swing as indicated by the arrow in Fig. 1 without moving said cam slide when the 20 bolt is retracted, and is provided with a cam face 48 against which the arm 41 contacts to move the slide 17 to revolve the bolt. The cam slide is slotted as at 49 to closely fit over the posts 19, so that the latter 25 act as a guide in the sliding movement of the plate, the metal bounding one side of the slot being the wall 16 before referred to, upon which rests the bolt shank 15.

A link or pitman 50 is pivotally connected to one end of this wall and the other end of the link is pivotally connected to the circumference of the collar 18, so that a movement of the cam arm 41 in reverse direction to that indicated in Fig. 1 will 30 cause a downward movement of the cam slide 17 which, through the pitman 50 and collar 18, will turn the bolt a half turn, or to jimmy proof position, such as indicated in Fig. 7, which shows the integral wings 35 51 of the bolt in horizontal position and therefore unseparable from the keeper plate 13, unless the bolt is moved so that the wings are vertical and in position to pass through the extended portions 52 of the bolt hole in said keeper, the latter of which 40 can only be done by a key from the outside of the door, or the knob from the inside of the door.

Referring further to the knob operated cylinder and in particular to the bolt operating finger 44 associated therewith, it will 50 be noted that the outer end of said finger passes under the arm 21 and is in position when operated to engage the widened part 55 22 of said arm. When this finger is revolved either by key or knob, it will force the arm 21 rearwardly, which will retract the bolt to allow the door to open as shown in Fig. 8.

The bolt will normally be in extended 60 position due to the spring pressure and will be held in position to pass through the keeper plate by the normal position of the cam slide 17, so that when the door is pushed 65 shut, the curved face of the bolt will be

cammed over the edge of the keeper to snap through the opening in the latter as is common in latch locks.

In order that the bolt wings cannot be thrown out of alignment with the corresponding extensions in the keeper when said bolt is being retracted, I provide a raised portion 53 on top of the bolt shank 15 between the collar 18 and the posts 19. Any slight retraction of the bolt will place 75 this raised portion between the posts 19 and prevent any revolving movement of the bolt. Also, and still more important, is the fact that this raised portion lies between one of the posts 19 and the collar 18 when the 80 bolt is revolved to jimmy-proof position, thus preventing any retractile movement of the bolt other than that given it by knob or key, as intended.

In operation, it is readily seen that the knob when turned toward the keeper will revolve the lower washer and throw the arm 41 downwardly to operate the slide 17, which in turn will revolve the bolt to jimmy-proof position. This same movement is given the arm 41 when the key is used because arm 34 will then be moved, and through the pin 46 will operate arm 41. A reverse movement of the knob or key will 95 give the complete operation. Assuming that the bolt is engaging the keeper in jimmy-proof position, a rotary movement of key or knob away from the keeper will cause an upward movement of the arm 41, referring to Fig. 9, which will operate against face 47 of the cam slide 17 until it has forced the latter upward sufficiently to let the arm 41 move freely past the same; at this time the bolt will, of course, be in position to allow its retraction, and then when the end 100 of the cut out portion 42 of the lower washer 40 contacts with the dowel 45 in the upper washer 43, said latter washer carries the bolt operating finger 44 into contact with the widened outer end 22 of the bolt retracting arm 21 and a continued movement of the finger 44 draws the bolt to the position shown in Fig. 8, or unlatched position. At 105 this time the bolt is under spring tension and should the key or knob be released, the bolt will be projected to the position shown in Figs. 1 and 3.

The mechanism operated by the key, in the cover plate for manipulating the arm 34, is substantially identical to that described for the knob and will cause the same movement to be imparted to arm 41, as caused by turning the knob.

It will be particularly noted that when the bolt is in retracted position, as shown in Fig. 8, a turning movement of the knob continuously toward the keeper will allow the bolt to move through the keeper and then turn the same to jimmy-proof position, as shown in Fig. 9.

- Thus I have provided a lock which is jimmy-proof, which can be used to guard against a person being locked out by the accidental closing of the door, as the bolt, when turned to jimmy-proof position when the door is opened, will prevent it from automatically latching should the door be blown shut by a draft or accidentally closed.
- Having described my invention, what I claim is:—
1. In a lock, a bolt, means associated with said bolt for normally holding it in extended position, a casing for said lock, a cover for said casing, a knob associated with said casing, and having a cylindrical portion thereon, a plurality of washers revolvably operated by said cylindrical portion, and means on said washers for causing the retraction and revolution of said bolt.
  2. In a lock, a casing, a bolt operable in said casing, a knob on said casing, a finger associated with said knob and disposed within said casing, a cover for said casing, a key operated lock associated with said cover, a cylindrical member revolvably mounted in said cover, a connection between the lock and the cylindrical member, an arm on said cylindrical member, and means associated with said knob and said arm whereby said bolt can be retracted or revolved upon a movement of the knob or the lock.
  3. In a lock, a bolt, a slide in said lock, a shank on said bolt, a collar on said shank through which said shank may have free sliding movement, and a pitman connecting said slide and said collar, whereby a movement of said slide will cause the rotation of said bolt.
  4. In a lock, a bolt, a square shank on said bolt, post members between which said square shank passes, said shank being rounded on its diagonally opposite corners in that portion which lies between the posts when the bolt is in normal position, so that said shank may revolve to cause the turning of said bolt member to a jimmy-proof position.
  5. In a lock, a bolt member adapted to be retracted or revolved, a shank member on said bolt, and a portion of said shank member having its diagonally opposite corners rounded whereby said bolt will be permitted to revolve only when it is in its normally projected position.
  6. The combination with a lock having a bevel headed bolt, of a keeper plate having a central opening and cut out portions extending from said opening through which said bolt is adapted to pass, a spring associated with the bolt, said bolt being provided with ears whereby it is prevented from passing through said keeper plate when said ears and said cut out portions are out of alignment and said bolt automatically serving as a latch when the said ears and cut out portions are in alignment.
  7. In a lock, a casing, an anti-jimmy bolt in said casing, a plurality of revolvable nested sleeves journaled in said casing, an operating arm on each of said sleeves, said sleeves when operated in one direction causing, through the medium of said arms, a projection of the bolt and a subsequent revolving movement thereof to anti-jimmy position.
  8. In a lock, a casing, a bolt, having a square shank, anti-jimmy projections on said bolt, a plurality of post members adjacent said bolt shank, a rounded portion on said shank, means whereby said shank can be revolved when the rounded portion thereof is between said post members, and means for moving the bolt to a position where its rounded portion is between said post members.

MORRIS SHEINMAN.
